UNITED STATES PATENT OFFICE.

HERBERT S. JANDUS AND CHARLES E. RASMUSSEN, OF DETROIT, MICHIGAN, ASSIGNORS TO THE C. G. SPRING & BUMPER COMPANY, OF DETROIT, MICHIGAN, A CORPORATION OF DELAWARE.

DESIGN FOR A CLAMP FOR VEHICLE BUMPERS.

Application filed May 19, 1927. Serial No. 22,072. Term of patent 14 years.

To all whom it may concern:

Be it known that we, HERBERT S. JANDUS and CHARLES E. RASMUSSEN, citizens of the United States, residing at Detroit, in the county of Wayne and State of Michigan, have invented a new, original, and ornamental Design for a Clamp for Vehicle Bumpers, of which the following is a specification, reference being had to the accompanying drawing, forming part hereof, wherein—

Fig. 1 represents a front elevation and Fig. 2 a side elevation of a clamp for vehicle bumpers exhibiting our new design.

We claim:

The ornamental design for a clamp for vehicle bumpers, as shown.

HERBERT S. JANDUS.
CHARLES E. RASMUSSEN.
